UNITED STATES PATENT OFFICE.

CHARLES T. CARLSON, OF CANTON, OHIO.

BURNING RACK.

Application filed July 17, 1924. Serial No. 726,496.

To all whom it may concern:

Be it known that I, CHARLES T. CARLSON, a citizen of the United States, residing at Canton, in the county of Stark and State 5 of Ohio, have invented a new and useful Burning Rack, of which the following is a specification.

This invention relates to racks such as are used for burning enameled ware, and 10 pertains more particularly to a rack provided with reversible pins for supporting the ware, and adapted to be used as a drying rack to dry the ware, and to be afterward placed in the furnace to burn the ware 15 without the necessity of rehandling the ware.

The objects of the invention are to provide a rack provided with a plurality of spaced openings or sockets adapted to receive double pointed pins, provided with a 20 central shoulder, whereby either end of the pin may be located in the socket and the opposite end exposed to support the ware; to provide a rack of this character adapted to first receive the wet enameled ware for 25 drying and to be afterward placed in the furnace without removing the ware, thus preventing unnecessary marring of the ware by removing from the drying rack to the burning rack; to provide a rack of this nature composed of two strips or bars of metal 30 provided at spaced intervals with registering arcuate portions and connected together between said arcuate portions by spot welding or the like, thus providing a plurality 35 of slightly elliptical sockets or openings to receive the pins; to provide double ended pins each having an annular shoulder midway between its ends, whereby the pins may be reversibly used upon the rack by insertion 40 into said sockets.

The above and other objects may be attained by constructing the rack in the manner shown in the accompanying drawing, in which—

45 Figure 1, is a perspective view of a rack embodying the invention;

Fig. 2, an enlarged side elevation of a portion of the rack;

Fig. 3, a fragmentary plan view of the 50 same;

Fig. 4, a section on the line 4—4, Fig. 2;

Fig. 5, a detached perspective view of one of the double ended pins;

Figs. 6, 7 and 8, perspective view of va-

rious shapes in which the rack may be made 55 for supporting articles of different shapes, and

Fig. 9, a fragmentary sectional perspective view of a modified form of rack.

Similar numerals indicate corresponding 60 parts throughout the drawings.

In the manufacture of enameled ware it is customary to dip the articles in a liquid solution of enamel, after which they are placed on a drying rack, from which they 65 are later removed and placed upon a burning rack which is put into the furnace with the ware thereon. This requires that the dry ware be removed from the pins upon the drying rack and re-placed upon the pins of the burning rack, frequently marring the portions of the ware engaged by the pins to such an extent that they cannot be sold as first class ware. The present invention 70 contemplates the provision of a metal rack 75 provided with double ended reversible pins for supporting the ware which is placed upon the pins to dry, the rack being then placed in the furnace for burning.

The preferred form of the rack illustrated 80 in Figs. 1 to 8 inclusive is formed of two bars or strips of steel 1 and 1^a provided at spaced intervals with a curved or arcuate depressions 2 and 2^a respectively, arranged to register as best shown in Fig. 3, forming 85 a slightly elliptical socket 3.

These bars are connected together, as by 90 spot welding or the like, at points indicated at 5, adjacent to each side of the socket thus formed.

Ordinarily these racks may be rectangular as shown in Fig. 1, the sockets being located in staggered relation, or in any other suitable arrangement. It may be desirable, 95 however, to form the racks of various shapes such as the triangular, circular and square racks shown in Figs. 6, 7 and 8 respectively.

Due to the extreme temperature of the furnace to which the burning racks are subjected, the points upon the pins of the racks 100 rapidly burn off, making it necessary to frequently sharpen all of the pins. In order to lessen this work I prefer to use a double pointed pin 6 detachably secured in the socket 3, and provided with a shoulder 7 105 midway of its length, whereby the pin is reversible and may be quickly detached and reversed when the upper end is worn, thus

making it possible to easily keep all of the pins of uniform length, and the points sharp.

As shown in Fig. 9, the rack may be formed of a single bar 1^b, provided with the socket 3^a to receive the pin. This form of rack may be used with the reversible pins above described, although it is obvious that the construction illustrated in Figs. 1 to 8 inclusive affords the better means for securely holding the pins in place within the rack, as when a pin is inserted the elliptical socket 3 is slightly sprung open, tightly gripping the pin, the shoulder upon the pin limiting the position of the same.

The metal rack above described is adapted to receive the freshly coated ware immediately after the same is dipped, and the ware may be left thereon to dry, after which the rack containing the ware is removed bodily and placed in the furnace for burning, thus obviating the necessity of removing the ware from the drying rack to the burning rack, as is customary under the present practice.

I claim:

1. A rack of the character described provided with spaced sockets, and a double ended pin having a shoulder midway of its ends and adapted to be reversibly inserted into each socket.

2. A rack of the character described pro-

vided with spaced, slightly resilient sockets, and a double ended pin having a shoulder midway of its ends and adapted to be reversibly inserted into each socket. 35

3. A rack of the character described formed of a pair of metal bars having spaced, registering arcuate portions, forming elliptic sockets, the bars being connected together at points near said sockets, and round pins adapted to be located in said sockets. 40

4. A rack of the character described formed of a pair of metal bars having spaced, registering arcuate portions, forming elliptic sockets, the bars being connected together at points near said sockets, and round pins adapted to be located in said sockets, and provided with shoulders for limiting their position in the sockets. 45

5. A rack of the character described formed of a pair of metal bars having spaced, registering arcuate portions, forming elliptic sockets, the bars being connected together at points near said sockets, and round pins adapted to be located in said sockets, said pins being provided with points at both ends and having shoulders midway of their ends. 50 55

In testimony that I claim the above, I have hereunto subscribed my name.

CHARLES T. CARLSON.
